UNITED STATES PATENT OFFICE.

ANTHONY HOZLAK, OF NANTICOKE, PENNSYLVANIA.

SUBMARINE ATTACHMENT.

1,262,500.

Specification of Letters Patent.

Patented Apr. 9, 1918.

Application filed December 26, 1917. Serial No. 208,920.

To all whom it may concern:

Be it known that I, ANTHONY HOZLAK, a citizen of Austria, residing at Nanticoke, in the county of Luzerne and State of Pennsylvania, have invented certain new and useful Improvements in Submarine Attachments, of which the following is a specification.

This invention relates to improvements in submarine attachments and it is the principal object of the invention to provide a novel attachment for use on submarine vessels whereby to permit the laying or placing of mines therefrom while submerged, thus, rendering the vessel extremely useful in warfare.

It is a more specific object of the invention to provide means for allowing a person to leave or enter the vessel while submerged without danger of flooding the interior thereof.

Other objects will be in part obvious and in part pointed out hereinafter.

The invention consists, furthermore, in the novel arrangement and combination of parts of the device as well as in the details of the construction of the same, all of which will be more fully described in the following specification and then finally embodied in the clauses of the claim which are appended to the specification and which form an essential part of the same.

In the drawings:—

Figure 1 is a top plan of the attachment as applied to a submarine vessel.

Fig. 2 is a vertical transverse section through the same, Fig. 3 is a longitudinal section therethrough and a portion of the submarine vessel, and,

Fig. 4 is a fragmentary section therethrough.

Having more particular reference to the drawings, in connection with which like reference characters will designate corresponding parts throughout the several views, 1 represents the hull of a submarine vessel in its entirety, one side of the same being provided with a way normally closed by a hingedly mounted door 2. Communicating with the way formed in the side of the submarine vessel is an inclosed way 3, the sides of which are obliquely disposed with relation to the sides of the submarine as indicated by the numeral 4, whereby to serve as means for deflecting the water contacting

therewith and preventing the abnormal straining of the inclosed way 3.

Arranged upon the outer end of the way 3 is a platform 5 having steps 6 arranged to one side thereof and leading to a point 60 above the inclosed way 3 and communicating with a second way 7 extending longitudinally thereof and opening on to the hull of the vessel 1.

A second door 8 is arranged in proximity 65 to the outer end of the inclosed way 3 and is mounted to swing inwardly thereinto in order that the same may be readily opened by a diver or other operator when so desired.

Formed in the bottom of the inclosed way 3, preferably intermediate the end thereof is an opening communicating with a tank or container 9 arranged therebelow and secured in a suitable manner to said inclosed 75 way. This opening, as will be noted, is normally closed by a vertically movable door 10 hinged at one end to the flooring of the inclosed way and adapted to lie flush with the same when in its closed position. A hand 80 hold 11 or other suitable device may be arranged upon the free portion of said door to facilitate lifting of the same to its open position.

In operation, the diver or other operator 85 when desiring to leave a submarine vessel provided with the improved device first opens the door 2 arranged in the side of the submarine vessel; it of course being understood that the outer door 8 arranged in the 90 way 3 is closed. Upon entering the inclosed way, the door 2 is then closed and the operator proceeds to the door 8, opening the same and passing onto the platform 5 from whence he can ascend by way of the steps 6 95 onto the inclosed secondary way 7 arranged above the inclosed way 3. Inasmuch as the way 7 opens onto the submarine hull, the operator may pass therefrom onto said hull and be in a position to facilitate the placing 100 or attaching of mines in an enemy's waterway or to an enemy's ship. When returning to the submarine vessel, the operator of course passes through the inclosed way 3 whereupon the door 8 thereof is closed. To 105 remove the water accumulated in said way, the vertically movable door therein is raised to its open position, thus, allowing such water instantly to pass into the tank 9. With the way thus cleared of the water, the op- 110

erator may then cause the door 2 to be opened and enter the submarine, whereupon said door is again closed.

Obviously, since the ways 2 and 7 and the 5 platform 5 are inclosed, all liability of the sweeping of the operator therefrom during movement of the submarine through a body of water will be prevented.

Manifestly, the construction shown is capable of considerable modification and such modification as is within the scope of my 10 claims, I consider within the spirit of my invention.

I claim:—

15 1. In combination with a submarine vessel, a door formed in one side thereof, an inclosed way communicating with said door, means for temporarily closing the outer end of said way, a second inclosed way arranged above the first way communicating

therewith and opening onto said vessel, and means arranged in the first way for removing water therefrom.

2. In combination with a submarine vessel, a door arranged in one side thereof, an 25 inclosed way secured to the submarine vessel and communicating with said door, the opposite sides of said inclosed way being arranged obliquely with relation to the sides of the submarine vessel, means for temporarily closing the outer end of the inclosed way, a second way arranged above and communicating with said first way and opening onto the hull of the submarine vessel, a tank 30 communicating with the flooring of said first way, and means for normally closing said tank.

In testimony whereof, I affix my signature hereto.

ANTHONY HOZLAK.
